UNITED STATES PATENT OFFICE.

ALBERT N. BAILEY, OF JOHNSTOWN, PENNSYLVANIA.

SATURATER-BELL.

SPECIFICATION forming part of Letters Patent No. 759,587, dated May 10, 1904.

Application filed December 7, 1903. Serial No. 184,095. (No model.)

To all whom it may concern:

Be it known that I, ALBERT N. BAILEY, a citizen of the United States, and a resident of Johnstown, in the county of Cambria and State 5 of Pennsylvania, have made a certain new and useful Invention in Saturater-Bells; and I declare the following to be a full, clear, and exact description of the same, such as will enable others skilled in the art to which it appertains 10 to make and use the invention, reference being had to the accompanying drawings, and to letters of reference marked thereon, which form a part of this specification.

Figure 1 is a central vertical section of my 15 invention. Fig. 2 is a plan view of the same. Fig. 3 is a view similar to Fig. 1 of my invention in place in the mold.

The invention relates to bells for saturater-boxes, such as are used in connection with 20 coke-ovens in making sulfate of ammonia; and the invention consists in the novel construction and combinations of parts, as hereinafter set forth.

In the accompanying drawings, illustrating 25 the invention, the letter *a* designates the bell, which may have any general form or contour, the round form being preferred. It consists, essentially, of a top or raised portion *b*, a skirt portion *c*, and flanges or lugs *d*, exteriorly arranged at the junction of the top and skirt 30 portions, said flanges or lugs projecting horizontally outward and being designed to support the bell in position in openings of the boxes, through which the skirt of the bell extends downward. The bell is provided with 35 an opening or openings in its top, as indicated at *e*, for the attachment of lead pipe. This bell is cast of lead in a suitable mold, in which is supported a cast-iron filler-top *f*, which 40 consists of a top portion *g*, short skirt portion *h*, and flanges or lugs *k*, all said parts being thinner than the finished bell and so disposed in the mold that the lead casting will cover in the filler-top and will descend below the 45 short skirt portion forming the deep solid lead extension *l*. An opening or openings are

made in the cast-iron top to provide for the opening or openings *e* of the bell. The openings made by the points of support of the filler in the mold are carefully filled in with lead. 50 This bell is thus made without jointing, and its top portion being strengthened by the filler it is very strong and durable, notwithstanding the efforts of heat and the fumes of sulfuric acid, as well as rough usage. 55

Having described this invention, what I claim, and desire to secure by Letters Patent, is—

1. A cast-lead saturater-bell having a strengthening cast-iron filler-top within the 60 upper portion of the bell, and a skirt portion descending below said filler-top, substantially as specified.

2. A cast-lead saturater-bell, having the perforated top portion, the descending skirt, the 65 exterior lugs at the junction of said top portion and skirt, and the cast-iron filler-top, within the top portion and lugs, covered in by the lead of the casting, substantially as specified. 70

3. A cast-lead saturater-bell, comprising a perforated top portion, descending skirt and exterior lugs at the junction of said top portion, and skirt, and the strengthening cast-iron filler-top within said top portion, and 75 lugs, and partly descending into the skirt, substantially as specified.

4. A cast-lead saturater-bell consisting of a perforated cast-iron filler-top having a top portion, a short skirt and exterior horizontal 80 lugs at the junction of the top portion and skirt, and around the same, a cast-lead bell covering in the cast-iron filler-top and descending below the short skirt portion thereof, substantially as specified. 85

In testimony whereof I affix my signature in presence of two witnesses.

ALBERT N. BAILEY.

Witnesses:

M. OPPERMANN,
W. P. REESE.
